Charles F. Dodge
His Esqfr.
By attorney

UNITED STATES PATENT OFFICE.

CHARLES F. DOBLE, OF WOLLASTON, MASSACHUSETTS.

DISHWASHING MACHINE.

Application filed July 10, 1922. Serial No. 574,059.

To all whom it may concern:

Be it known that I, CHARLES F. DOBLE, a citizen of the United States, residing at Wollaston, county of Norfolk, Commonwealth of Massachusetts, have invented certain new and useful Improvements in Dish-washing Machines, of which the following is a specification.

This invention relates to dish washing machine, and particularly to the water action thereof.

The object of my invention, generally stated, is to provide for a more thorough and efficient cleansing of the dishes than has heretofore been attained.

To this end, the dishes are supported in the upper portion of the tank and the washing fluid is simultaneously projected upwardly past the dishes and downwardly thereupon in a revolving sheet whereby to uniformly cover and thoroughly cleanse both faces of the dishes.

In the embodiment of my invention illustrated in the present application, the upward and downward projection of the water over the dishes is accomplished by a rotary propeller and a rotary pump, respectively, which are both mounted within the tank for rotation about a common axis and in addition revolve as a unit over the tank bottom about an axis transverse to their axis of rotation whereby to project the water as a revolving sheet in a multitude of directions over the dishes. In this application the propeller and pump are simultaneously rotated and revolved by a motor located exteriorly of the tank.

In addition to its water distributive action during the washing operation, the rotary pump may be utilized to fill or empty the tank where no direct pipe connection to the water supply and drain is available, thus reducing the installation cost of the machine by obviating the necessity for any expensive modification of existing plumbing facilities.

The construction and operation of my invention are described and shown in the accompanying specification and drawings and the characteristic features of novelty are particularly pointed out in the appended claims. Throughout the specification and drawings like reference characters are correspondingly applied, and in the drawings:

Fig. 1 is a vertical longitudinal section

through a dishwashing machine in accordance with my invention and indicating in dotted lines the hose connection for adapting the pump for use in filling or draining the tank.

Fig. 2 is a top plan view thereof with the cover open and the dish rack removed and indicating in full and dotted lines the revolving movement of the propeller and pump about the bottom of the tank during the washing operation.

Figs. 3 and 4 are detail views at the delivery end of the discharge pipe from the rotary pump particularly showing the nozzle construction, and

Fig. 5 is a detail view at the delivery end of said pipe, particularly showing the swivel connection for the filling and draining hose.

I have indicated at 1 a base ring to which is connected a plurality of suitably braced legs 2 for supporting the tank 3 of the washer at a proper elevation.

Suspended within the tank above the water level and in superposed relation to each other are, respectively, a dish rack 4, a silver tray 5 and a tumbler basket 6.

Mounted exteriorly of the tank, preferably therebeneath, is an electric motor 7. The motor shaft 8 is separably connected by a universal joint 9 with a vertically disposed drive shaft 10. The shaft 10 extends through the tank bottom substantially axially thereof, the opening in the tank bottom being closed by a stuffing box 11, and within the tank is journaled in a bearing 12 resting upon the tank bottom.

Revolute upon the bearing 12 as an axis is a rotor casting 12' comprising spaced bearing uprights 16 at one side of the axis of revolution and a pump casing 19' at the other side of said axis.

Journaled in said bearings 16 and in the pump casing is a horizontal shaft 13 which is rotated from the drive shaft 10 by intermeshing gears 14 and 15, respectively, on said shafts.

Fast on the shaft 13 between the bearings 16 are arms 18 carrying a pair of oppositely disposed water projecting blades or propellers 17 for projecting the water upwardly over the dishes in a revolving stream under the combined rotation and revolution of the shaft 13. The blades 17 are partially inclosed within a screen 28 carried by the bearings 16 and direct the water against a

curved deflector or apron 16^a which extends in close proximity to said blades throughout substantially the lower quadrant of their movement and like the screen follows the 5 revolution of the blades over the tank bottom. See Fig. 2. The bearings 16 are preferably connected by a plurality of spaced longitudinally extending tie rods 16^b.

Fast on the shaft 13 within the pump casting 19^a at the opposite side of the axis of revolution of said shaft is a bladed rotary piston 19. Water is admitted into the casting to said piston through an inlet pipe 20^a, the intake end of which is provided with a 10 removable screen 20^a, and is projected upwardly by said piston through the outlet 20^b of the casing into a delivery pipe 20 which is preferably bent to pass upwardly through the superposed dish rack, silver tray and 15 tumbler basket in substantially the longitudinal axis of the tank.

Fitted to the upper end of said pipe 20 is a discharge nozzle 21 which is provided with an elongated discharge port 22 adapted to 20 project the water in a revolving sheet over the dishes as the casting 12^a is revolved about a vertical axis over the tank bottom. (See Fig. 2.)

By my invention the water projecting 30 blades 17 and the rotary pump piston 19 are simultaneously rotated about a horizontal axis (the shaft 13) and revolved as a unit about a vertical axis (the shaft 10) so as to project the water both upwardly and 35 downwardly and at multitudinous angles over the dishes.

The nozzle 21 is made detachable so that it may be removed and a hose 23 connected with the pipe 20 to permit the tank to be 40 filled through the pump where there is no direct pipe connection to the water supply.

In order to adapt the pump for emptying the tank under similar conditions, I provide a swivel connection 24 (Fig. 5) which may 45 be substituted for the nozzle 21 to which the hose 23 may be attached. With such connection when the pump is started to empty the tank, the swivel connection 24 permits the hose 23 to remain stationary as the pump 50 revolves over the tank bottom.

Preferably the hose 23 is led into the tank through a hole 25 (Fig. 1) in the hinged tank cover 26, said hole being normally closed by any suitable threaded cap (not 55 shown).

Let into the bottom of a tank is a drain fitting 27 with which a sewer connection may be made if desired, and the tank will, of course, also have a filling connection.

As will be evident, the separable connection at 9 permits the shafts 8 and 10 to be disconnected and the rotor, propeller and pump to be bodily removed from the tank for purposes of cleaning or repair.

Various modifications in the construction

and operation of my device may obviously be resorted to without departing from the spirit of my invention if within the limits of the appended claims.

What I therefore claim and desire to secure by Letters Patent is:

1. In a dish washing machine, a tank, means for supporting dishes therein, a rotary propeller and a rotary pump mounted within said tank, for simultaneous rotation 75 about a common horizontal axis, and effective to project water upwardly past and downwardly upon the dishes, and means for simultaneously revolving said propeller and pump about a common vertical axis, whereby to project the water against the dishes in a revolving sheet.

2. In a washing machine, a tank, means for supporting dishes therein, a rotary propeller and a rotary pump supported within 80 the tank at opposite sides of the vertical axis of the tank for projecting water upwardly past and downwardly upon the dishes and means for revolving said propeller and pump about the vertical axis of the tank, 85 to project the water against the dishes in a revolving sheet.

3. In a washing machine, a tank, means for supporting dishes therein, a rotor shaft journaled in said tank, a bladed propeller and a rotary pump mounted on said shaft at opposite sides of the vertical axis of the tank for projecting the water upwardly past and downwardly upon the dishes, and means whereby said shaft is simultaneously rotated and revolved about axes of rotation and revolution in relative angular disposition to each other to project the water against the dishes in a revolving sheet.

4. In a washing machine, a tank, means for supporting dishes therein, a rotor within 95 said tank, a bladed propeller and a rotary pump carried by said rotor for projecting water upwardly past and downwardly upon the dishes, means for simultaneously rotating and revolving said propeller and pump about axes of rotation and revolution at 100 right angles to each other to project the water against the dishes in a revolving sheet.

5. In a washing machine, a tank, means for supporting dishes therein, a rotor within 110 said tank, a bladed propeller and a rotary pump carried by said rotor for projecting water upwardly past and downwardly upon the dishes in a revolving sheet, and a motor mounted exteriorly of the tank for simultaneously rotating and revolving said propeller and pump about axes of rotation and revolution at right angles to each other.

6. In a washing machine, a tank, means for supporting dishes therein, a rotary pump within the tank having a discharge 115 downwardly onto the dishes from a point above, and means for rotating and revolv-

ing said pump about axes of rotation and revolution in relative angular disposition to each other.

7. In a dish washing machine, a tank and a pump mounted therein for simultaneous rotation and revolution about axes of rotation and revolution in relative angular disposition to each other, a delivery pipe from said pump, and a hose having a 10 swivel connection with the discharge end of said pipe.

8. In a dish washing machine, a tank, means for supporting dishes therein, a rotor mounted on a vertical axis within said tank, 15 a shaft journaled horizontally in said rotor, a bladed propeller and a rotary pump on said shaft at opposite sides of the vertical

axis of the tank for projecting water upwardly past and downwardly upon the dishes in a revolving sheet, and a motor 20 mounted exteriorly of the tank and operatively connected to said rotor for simultaneously rotating and revolving said shaft about axes of rotation and revolution at right angles to each other, said pump having a delivery pipe extending along the vertical axis of the tank and terminating in a downwardly directed discharge. 25

In testimony whereof I affix my signature in presence of two witnesses.

CHARLES F. DOBLE.
